INVENTOR

UNITED STATES PATENT OFFICE

GUY W. SMITH, OF KALAMAZOO TOWNSHIP, KALAMAZOO COUNTY, MICHIGAN

ROSIN-RECLAIMING MACHINE

Application filed March 16, 1928. Serial No. 262,258.

The main objects of this invention are:

First, to provide a rosin reclaiming machine for recovering rosin from the emptied container that is very simple in construction and effective in operation.

Second, to provide a means for collecting the rosin after removing the same from the barrel staves.

Third, to provide a means whereby the staves of emptied rosin barrels can be driven at a speed to be thoroughly cleaned.

Objects pertaining to details and economies of construction and operation will definitely appear from the description to follow.

15 The invention is defined in the claims.

A device embodying my invention is clearly illustrated in the accompanying drawing, in which:

20 Fig. 1 is a perspective view of my improved reclaiming machine, parts being broken away for clearness and convenience in illustration, only a portion of the collecting box and receptacle being shown.

25 Fig. 2 is a vertical section on line 2—2 of Fig. 3, a stave inserted in the machine indicating the process of beating and the machine being at a standstill.

30 Fig. 3 is a partial longitudinal section on line 3—3 of Fig. 2, parts being shown in full lines.

The parts of the drawing will be referred to by their numerals of reference which are the same in all the views.

35 1 is the frame of my improved rosin reclaiming machine. 2 are the supporting legs therefor. 210 are the cross members. 3 are intermediate cross supporting members. 4 is the drive shaft, 41 is the drive pulley and 42 are the journal supports. 5

40 is my improved beater drum secured to the drive shaft by any suitable means. 51 are pivotally mounted beaters of a single link construction and 52 are slots in the drum. 53

45 are connecting links inserted therethrough for pivotally mounting the beaters. 54 are locking links inside the drum.

50 6 is the table support for the work consisting of parts 61 and the slightly inclined part 62. A way 63 is formed between the two inner ends of the parts 61 and 62. 64

is a cross bar for supporting the table. 65 is an adjustable guide.

7 is a shaft with its top side exposed to act as a feed roll for conveying the staves through the machine. 71 is a pulley 55 mounted on the shaft or roll having a frictional driving means 72 coating with the drive shaft 4 to be driven at slow speed. 73 are journal supports for the shaft 7.

8 are the side walls of an enclosed suction chamber. 81 is the top and 9 are the end walls. 91 are flexible depending strips secured to the same for closing the end of the chamber when the staves are not being passed through.

10 is a suction fan. 101 is a bracket for supporting the fan. 102 is the intake connection to the fan leading from the suction chamber. 103 is a hopper-like connection from the suction chamber. 104 is a downwardly projecting flange on the end of the hopper for supporting the depending flexible strips 105 of leather or a suitable material, forming a flexible curtain for the discharge opening for the staves.

11 is a discharge nozzle for the fan. 111 is the rosin dust collecting chamber of framework covered with porous fabric. 112 is the rosin collecting receptacle beneath the chamber. 12 is a barrel stave.

With these parts thus arranged a very practical rosin reclaiming machine has been produced. The staves of emptied rosin barrels as they come from the consumer of rosin are coated with a considerable amount of rosin which, of course, is waste, and this machine reclaims the same by beating and collecting, although my machine does not remove all the rosin. A small amount is partially impregnated in the wood and can not be separated by beating.

85 The staves are inserted two at a time, this being all that can be easily handled by a man feeding the machine. After the staves are fed into the machine, the action of the beaters on the staves tends to drive them through the machine. To facilitate the driving, the roller shaft 7 is provided to frictionally engage the bottom of the staves and carry them through.

As the staves are passed through they are brushed by the flexible strips which help to retain the rosin dust in the suction chamber by causing a restricted inflow of air against the staves. The rosin dust and chips are taken through the fan and discharged into the dust chamber. The chamber in this embodiment is a square frame 112 covered by any suitable porous fabric that allows the air to effectively pass therethrough. The collected rosin may be passed through a general process of refining. The beaters 51 are of the single link type supported by a link 53 through the slots 52 in the drum.

The beaters are set in a staggered relation to beat the entire width of the stave as it passes through the machine. Although a plurality of links can be used with the same results, the only objection to using the plurality is that there are too many wearing surfaces to make this practical. A bar of metal perforated at one end and pivotally mounted on the link 53 would also do the work with the desired effect.

Having thus described my invention what I claim as new and desire to secure by Letters Patent is:

1. A machine for recovering rosin from used barrel staves comprising a suitable table, a suction housing above the said table with curtained apertures at front and rear for the passage of staves, a beater drum disposed in the said housing with single link beaters pivotally connected to the exterior of said drum and adapted to swing downwardly to beat the rosin coated surfaces of a barrel stave passing therethrough, a feed roll comprising a shaft disposed in a recess in the top of a table to slowly advance the staves fed therethrough, a friction drive therefor from the beater drum shaft, a suction fan, the intake of which is connected to the said suction chamber to induce a strong inward current of air entering the said chamber to retain and withdraw the powdered rosin, and a collector to which said fan delivers covered with porous fabric to receive the discharged rosin, as specified.

2. A machine for recovering rosin from used barrel staves comprising a suitable table, a suction housing above the said table with curtained apertures at front and rear for the passage of staves, a beater drum disposed in the housing with single link beaters pivotally connected to the exterior of said drum and adapted to swing downwardly to beat the rosin coated surfaces of a barrel stave passing therethrough, a feed roll comprising a shaft disposed in a recess in the top of a table to slowly advance the staves fed therethrough, a friction drive therefor from the beater drum shaft, a suction fan, the intake of which is connected to the said suction chamber to induce a strong inward current of air entering the said chamber to

retain and withdraw the powdered rosin, and a collector to which said fan delivers, as specified.

In witness whereof I have hereunto set my hand.

GUY W. SMITH.
